MIXING FORK OR THE LIKE

Virginia B. Gay, 34 E. 48th St.,
Savannah, Ga. 31405

Filed Jan. 6, 1969, Ser. No. 15,262

Term of patent 14 years

Int. Cl. D7—03

U.S. Cl. D44—29

FIG. 1

FIG. 2

FIG. 3

FIG. 1 is a left side elevational view of a mixing fork or the like, showing my new design;

FIG. 2 is a top plan view;

FIG. 3 is a right side elevational view, partly broken away for convenience of illustration; and

FIG. 4 is an end elevational view thereof.

I claim:

The ornamental design for a mixing fork or the like, as shown.
